UNITED STATES PATENT OFFICE.

WILLIAM JEFFERSON CONNALLY, OF ATLANTA, GEORGIA.

HORSESHOE.

No. 830,133.

Specification of Letters Patent.

Patented Sept. 4, 1906.

Application filed November 21, 1905. Serial No. 288,398.

To all whom it may concern:

Be it known that I, WILLIAM JEFFERSON CONNALLY, a citizen of the United States, residing at Atlanta, in the county of Fulton 5 and State of Georgia, have invented new and useful Improvements in Horseshoes, of which the following is a specification.

My invention pertains to horseshoes of the removable-calk type; and it has for one of its 10 objects to provide such a horseshoe embodying a simple and strong construction calculated to effectually prevent casual displacement of its calks and yet permit of any one of the calks being quickly and easily removed 15 and as readily replaced with a new calk when necessity demands.

Another object of the invention is the provision of a horseshoe of the removable-calk type in which the calks are efficiently 20 cushioned with a view of preventing the transmission of shock and jar to a horse's hoof.

Other advantageous features peculiar to my invention will be fully understood from 25 the following description and claims when the same are considered in connection with the accompanying drawings, forming part of this specification, in which—

Figure 1 is an inverted plan view of the 30 horseshoe constituting the present and preferred embodiment of my invention. Fig. 2 is a longitudinal central section of the same. Fig. 3 is a detail transverse section taken in the plane indicated by the line 3 3 of Fig. 1. Fig. 4 is a detail longitudinal section taken 35 through the toe-calk and its holder and the adjacent calk-retainer. Fig. 5 is a detail transverse section taken in the plane indicated by the line 5 5 of Fig. 1 and illustrating 40 the manner in which the calk-retainers are engaged with the body of the horseshoe, and Fig. 6 is a perspective view of one of the calk-retainers removed.

Similar letters designate corresponding 45 parts in all of the views of the drawings, referring to which—

A is the body of my novel horseshoe, which is of the ordinary general form and is preferably made of the metal usually employed, 50 and B and C C are calk-holders formed integral with the body and designed for the reception of a removable toe-calk B' and removable heel-calks C' C', respectively. The calk-holder B is curved throughout its length, 55 is closed at one end, as indicated by a, and is provided on the lower edges of its side walls

with inwardly-directed flanges b. The calk-holders C C differ from the holder B in that they are straight. They are, however, closed at their rear ends, as indicated by c, 60 and are provided on the lower edges of their side walls with inwardly-directed flanges d. The calk B' is curved throughout its length, while the calks C are straight; but with this exception the calks are identical in construction—that is to say, they respectively comprise a body e, which may be toothed on its under side, as indicated by f, or plain, as desired, and a T-head g, the said T-head being designed to be engaged by the inwardly- 65 directed flanges of the calk-holders after the manner shown with a view of precluding casual displacement of the calks while the shoe is in use.

E E are cushions of rubber or other suitable material arranged in and extending the full length of the calk-holders and having for their purpose to prevent the transmission of shock and jar to a horse's hoof, and F F are plates of steel or other suitable material interposed between the calks and the cushions. These plates F have for their office to facilitate introduction of the calks into the holders subsequent to the placing of the cushions in said holders and to prevent disarrangement of the cushions incident to the introduction of the calks. In this connection it will be noticed that the ends of the calks adjacent to the closed ends of the calk-holders are beveled, as indicated by h, this latter 90 provision being made in order to enable the calks to slide readily over the plates F.

In addition to the calk-holders B and C the body A is provided with the usual nail-holes i and with depending ribs or flanges j and 95 notches k, the said ribs or flanges j extending crosswise of the body at points adjacent to the open ends of the calk-holders, and the notches k being formed in the inner edge of the body. It will also be seen by reference to Fig. 4 of the drawings that the open ends 100 of the calk-holders are provided at points immediately adjacent to the under side of the body A with recesses l.

G G are the calk-retainers of the shoe, of 105 which there is one employed in connection with each calk and the holder thereof. These calk-retainers respectively comprise a body m, having a nail-hole n adapted to coincide with one of the nail-holes i in the body A, a 110 flange p depending from one end of the body m and arranged to abut against the open end

of one calk-holder and one end of the calk therein, a projection *q* extending from the opposite end of the body *m* and arranged to bring up against the outer end of one rib or 5 flange *j*, a projection *r* extending inwardly from the inner edge of the body *m* and designed to be bent into one of the notches *k* of the body *A* after the manner shown in Fig. 5, and a tongue *s*, extending from the same end 10 of the body *m* as the flange *p* and designed to rest in one of the recesses *l* of the body. When the several calk-retainers *G* are arranged, as shown in Fig. 1, relative to the body *A* and are connected by nails to the 15 said body and to a horse's hoof, it will be apparent that the flanges *p* will preclude casual displacement of the calks from the calk-holders, while the projections *q* and *r* and the tongues *s*, coöperating with the ribs or flanges 20 *j*, the notches *k*, and the recesses *l*, respectively, of the body *A* will effectually prevent casual movement of the calk-retainers with respect to the said body *A*.

It will be apparent from the foregoing that 25 when the parts of the horseshoe are assembled and connected together, as shown in Fig. 1, there is no liability of any one of the calks working loose or being casually displaced. When, however, it is necessary for 30 any reason to remove any one of the calks and replace the same with a new calk, the same may be quickly and easily accomplished after the retainer complementary to the said calk is disconnected from the body *A* and the 35 horse's hoof by drawing the nail which extends through the said retainer. In this way one or all of the calks may be expeditiously removed and replaced with new calks without the necessity of removing the body *A* 40 from the horse's hoof, which is an important desideratum.

It will also be gathered from the foregoing that my novel shoe is no more cumbersome and heavy than the ordinary shoe at present 45 in general use, and yet it is calculated to enable a horse to secure a good foothold on a slippery surface and at the same time efficiently cushion the horse's hoof incident to travel over a hard roadway. It will further 50 be noticed that my novel horseshoe embodies no delicate parts, such as are likely to get out of order after a short period of use, and that it is adapted to withstand rough usage quite as well as a horseshoe of the ordinary well-known construction. In fact, my novel horseshoe, as a whole, will obviously last 55 longer than an ordinary horseshoe, because when the calks *B* and *C* are worn to a greater or less extent they may be readily removed 60 and replaced with new calks.

With a view of preventing injury to the cushions of the horseshoe when great weight is imposed on the cushions I provide the abutments *m*³ in the upper portions of the calk-holders. The plates *F* or the upper sides of

the **T**-heads of the calks bring up against said abutments *m*³ when the cushions are unduly compressed, and thereby obviate injury to the cushions.

I claim—

1. In a horseshoe of the removable-calk type, the combination of a body having a calk-holder closed at one end and open at its opposite end and provided with a contracted lower portion; said body also having a cross-wise rib, a calk removable from the holder in the direction of the length of the body, and a calk-retainer removably secured on the body between the crosswise rib thereof and the open end of the calk-holder. 70

2. In a horseshoe of the removable-calk type, the combination with a body having a calk-holder closed at one end and open at its opposite end and having flanges extending inwardly from its side walls, whereby its lower portion is contracted; of a calk removable from the holder in the direction of the length of the body and comprising a body and a **T**-head resting in the calk-holder, and a calk-retainer secured on the body adjacent to the open end of the calk-holder. 85

3. In a horseshoe of the removable-calk type, the combination with a body having a calk-holder closed at one end and open at its opposite end, and also having a crosswise rib 95 on its under side and a notch in its inner edge and a recess in the open end of the calk-holder; of a calk removably arranged in the holder, and a calk-retainer disposed between the rib or flange on the body and the open 100 end of the holder and having a projection arranged to bear against the outer end of the rib or flange, a projection bent into the notch of the body, and a tongue disposed in the recess in the end of the holder, said retainer being adapted to be detachably connected to the body. 105

4. In a horseshoe of the removable-calk type, the combination with a body having a calk-holder closed at one end and open at its 110 opposite end and provided with inwardly-extending flanges on its side walls, and also having a crosswise rib on its under side and a notch in its inner edge and a recess in the open end of the calk-holder; of a calk removably 115 arranged in the holder and comprising a body and a **T**-head, and a calk-retainer disposed between the rib or flange on the body and the open end of the holder and having a projection arranged to bear against the outer end of 120 the rib or flange, a projection bent into the notch of the body, and a tongue disposed in the recess in the end of the holder, and also having a nail-hole arranged to coincide with a nail-hole in the body. 125

5. In a horseshoe of the removable-calk type, the combination of a body having a calk-holder closed at one end and open at its opposite end and provided with a contracted lower portion; said body also having a recess 130

in the open end of the calk-holder and a crosswise rib arranged adjacent to said open end, a calk removable from the holder in the direction of the length of the body, a calk-retainer arranged in the recess in the open end of the calk-holder and against the adjacent side of the crosswise rib and removable from the body in the direction of the width thereof, and means for securing the retainer on the body.

6. In a horseshoe of the removable-calk type, the combination of a body having a calk-holder open at one end and closed at its opposite end and having a contracted lower portion, a calk removable from the holder in the direction of the length of the body and having an enlarged upper portion, a cushion arranged in the holder, between the calk and the body, and also removable from the holder in the direction of the length of the body, and means for retaining the calk and the cushion in the holder.

7. In a horseshoe of the removable - calk type, the combination of a body having a
25 calk-holder, a calk removably arranged in the holder and having its upper side beveled at
one end, a cushion disposed in the holder above the calk, and a metallic plate arranged
in the holder and interposed between the up-
30 per side of the calk and the under side of the
cushion.

8. In a horseshoe of the removable-calk type, the combination with a body having a calk-holder open at its under side and at one end and provided with inwardly-directed flanges at the lower edges of its side walls; of a removable calk having an enlarged upper por-

tion held against downward movement in the
calk-holder, a cushion removably arranged in
the holder between the upper side of the calk 40
and the body, and a removable retainer clos-
ing the open end of the holder, the body and
the said retainer being provided with coöper-
ating means whereby the retainer is held
against casual movement on the body. 45

9. In a horseshoe of the removable-calk type, the combination with a body having a calk-holder open at its under side and at one end and provided with inwardly-directed flanges at the lower edges of its side walls; of a removable calk having an enlarged upper portion held against downward movement in the calk-holder, and also having its upper side beveled at one end, a cushion removably arranged in the holder at a point above the calk, a plate interposed between the calk and the cushion, and a retainer detachably held on the body. 45 50 55

10. In a horseshoe, the combination of a body having a calk-holder provided in its upper portion with abutments and also provided at its lower portion with inwardly-directed flanges, a calk having a T-head or enlargement disposed in the holder and movable between said abutments and flanges, and a cushion interposed between the calk and the top of the holder. 60 65

In testimony whereof I have hereunto set my hand in presence of two subscribing witnesses.
